SAFETY CONTROL FOR HOISTS AND CIRCUIT THEREFOR

Harry F. Vickers, Detroit, Mich., assignor to Vickers Incorporated, Detroit, Mich., a corporation of Michigan

Application December 3, 1936, Serial No. 114,008

15 Claims. (Cl. 198—37)

1

This device concerns a safety control for hoists and circuit therefor, and has to do particularly with a hoist adapted to convey articles from one station to another and means for controlling the movement of said hoist in either direction between the said stations.

The present device operates by means of a chain type conveyor hydraulically driven and supplemented by a system of controls both hydraulic and electric, which is believed to be a new idea, when considered together with the safety locking device.

An object of this invention is to provide an automatic control of starting, stopping and direction of travel, when certain requirements of these functions are to be fulfilled, said control being practically free of any parts that are apt to get out of order or lack dependability in operation.

Other objects will be apparent from the following description and claims when considered together with the accompanying drawings.

In the drawings:

Fig. 1 is a flow chart largely diagrammatic, of a chain type hoist and circuit therefor, with the control valves in section, and showing the relative position of valves at the first stage of operation or with both stations loaded.

Fig. 1a is a diagrammatic illustration of the hoist showing both stations loaded and the relative position of the switches.

Fig. 2 is a view similar to Fig. 1, showing the relative position of parts during the second stage of operation, or with the lower station empty.

Fig. 2a is a view similar to Fig. 1a showing the lower station empty and the upper station loaded.

Fig. 3 is a view similar to Fig. 1 but illustrating the position of various parts and operation of circuit during the downward motion of the conveyor, both stations being empty and the article in transit.

Fig. 3a is a view similar to Figs. 1a and 2a showing both stations unloaded and a projectile in transit.

The illustrated embodiment of this invention includes, a delivery station X which may be termed an upper station, a loading or lower station Y, and a chain type conveyor diagrammatically illustrated by the dotted line Z and operatively connected to a hydraulic motor diagrammatically illustrated as at H. The conveyor Z which may be any kind of an endless conveyor unit, is adapted to be actuated simultaneously with the shaft T, one end of which is operatively connected to a hydraulic motor H and the other end to an automatic control unit generally designated U; in other words, the drive is usually from the hydraulic motor H through suitable reduction gearing to the conveyor Z and to the control shaft T. The unit U also includes a latch and cam mechanism operatively connected

2

with valve mechanisms for controlling the step by step movement of the conveyor, including a directional stop control D. The endless conveyor unit above referred to is illustrated and described in detail in my copending application, Serial No. 35,607, filed Aug. 10, 1935.

Fluid under pressure is supplied by a pump 1, of the constant displacement type, supplying fluid from tank reservoir 2 under pressure to conduit 3. The pressure in conduit 3 is limited by vented relief valve 4 which operates in the following manner: Through small orifice 5 in piston 5a the pressure in conduit 3 is transferred to chamber 6, causing a balance between the said chambers. With spring 7 set to an initial pressure of approximately 20# per square inch, the resulting pressure to the left of piston 5a, as viewed in the drawings, is approximately 20# per square inch more than the normal operating pressure in chamber 6 and conduit 3. This pressure to the left of the valve urges it to closed position. The maximum relief pressure is controlled by an emergency relief valve 8, which by the adjustment of the spring limits the pressure in chamber 6. If venting line 9 is connected to the tank or atmosphere, this removes the effect of pressure in chamber 6, causing the pressure in conduit 3 to fall to the pressure as limited by spring 7 which is still acting on the piston.

30 On diametrically opposite sides of the automatic control unit U are located a cam lever a and a latch b and auxiliary control piston valves A and B. The cam operated acceleration-deceleration valve A is on the left hand side of the automatic control unit, as in Fig. 1; and the latch operated valve B is on the right side of the automatic control unit. The valve B is connected by conduits to a solenoid operated starting valve C which is connected by conduit 3 to the pressure fluid through the vented relief valve 4. The directional valve D is connected through conduits 18 and 19 to the hydraulic motor H to control the direction of movement of the hoist. The above mentioned valves A, B, C and D have 45 intercommunicating connections for reception of a pressure fluid, and for actuation of the conveyor when certain conditions exist.

To better understand the operation of the circuit and control of the conveyor motor it is 50 thought best to set forth the primary conditions desirable for obtaining automatic control in a predetermined direction, as follows:

(1) With the upper station filled, and the knob of directional valve D set to lowering position, 55 the conveyor Z should move downward only when the lower station Y is empty.

(2) With both upper and lower stations X and Y empty, it is important that no motion of the conveyor should ensue irrespective of the setting 60 of the knob of directional control valve D.

(3) With both stations filled, as shown in Fig. 1a, it is important that no motion shall ensue, irrespective of the setting of the directional control valve D.

(4) With the upper station empty and the directional control valve D set to "hoist" the motion should be upward only when the lower station is filled.

The preferred means for deriving the required results when any of the above listed conditions are met with, is what is commonly called a three point electric control circuit, embodying two two-way article sensitive limit switches S₁ and S₃ interposed by a four-way switch S₂, as will be subsequently described. The switches S₁ and S₃ are so positioned adjacent the stations X and Y as to be actuated or released by the presence or absence of articles at the respective stations.

Figs. 1 and 1a illustrate the third condition of operation, the upper station switch S₁, being correspondingly set for a filled condition. The intermediate four-way switch S₂ is attached to the directional control valve D to effect a transposition of control wires E₁ and E₂ whenever the directional control valve D is shifted. With the lower station two-way switch S₃ set to a filled position, the electrical circuit line E₃ and E₄ is opened causing a solenoid E₅ to be ineffective. With the valves B and C of Fig. 1 in the inactive position, the venting line 9 through the corresponding ports is opened to the tank through the channels 9, 10 and 11 allowing the described fall in pressure, by means of the vented relief valve 4.

Figs. 2 and 2a illustrate the first condition of operation, the switches S₁, S₂ and S₃ being so interconnected as to magnetically actuate the valve C. With the knob of directional control valve D set to lower, the movement of starting valve C to the left causes the following consecutive functions. Fluid flow through the venting line 9 is cut off by closing ports 36 and 37 allowing the pressure in conduit 3 to build up to the required resistance. By this movement of the valve C the pressure conduit 3 is opened through a conduit 12 to port 13 of valve B and with a clear channel to port 14 and conduit 15. With the directional control valve D in the position shown in Fig. 2, conduit 15 is connected through ports 16 and 17 with a "lower" setting of the directional valve D, and finally through the conduit 18 to tend to drive the motor momentarily in a lifting direction. At this described position of the valve D the return fluid is directed from channel 19 through the open ports 20, 21 to conduit 22 through port 23, and open port 24, which finally connects to the conduit 11, a tank connection. Pressure in the conduit 15 is maintained to the required value by the spring loaded check valve 25, the function of which will be subsequently described more in detail. By a further movement of starting valve C, pressure conduit 3, through port 26 and conduit 27, applies pressure to chamber 28, effecting a withdrawal of the motor holding latch b. This withdrawal occurs during the momentary lifting movement of the motor.

With the withdrawal of the latch b and attached valve B, the conduit 22 is diverted from the tank port 24 to the pressure conduit 29, effecting a reversal of the fluid flow to the motor, (see the position of valve B in Fig. 3).

Momentarily after the valve B is moved to the right (as in Fig. 3), the starting valve C still remains to the left as shown in Fig. 2, allowing a clear channel for the return fluid from the motor

through the line 18, ports 17 and 16 to the spring loaded back pressure valve 25, which offers a back pressure to the return flow of the motor to prevent over-run when lowering. From the spring loaded valve 25, the return fluid has free access to the tank through conduit 30 and ports 31 and 11.

Now after motion has started in the downward direction, as shown in Fig. 3a, the upper article, being in transit, allows movement of switch S₁ by reason of its spring 32 to divert the electrical flow of current from line E₂ to E₁, thereby de-energizing solenoid E₅ and allowing starting valve C to return to normal as indicated. The member U is provided with a cam lobe a'; the timing of the cam lobe a', actuating valve A, and the shifting of the electrical switch S₁, are so arranged that a movement to the right of auxiliary control valve A precedes the shift of S₁. The purpose of this timing relationship, or lost motion, is to allow a continued free flow of the return fluid from the motor before the valve C returns to normal. With the lobe of the cam beyond the roller of valve A, spring 33 forces valve A to the right as limited by the dwell on the cam as shown. With the valve A in this position the return fluid from the motor is directed from the conduit 30 to the ports 34 and 35 to the tank conduit 11. By reason of the venting ports 36 and 37 of valve C and ports 10 and 24 being connected in series, venting of the relief valve is prevented and pressure maintained by the closure to port 24, regardless of the return of valve C. With the return of the valve C to normal the port 26 is diverted to conduit 11, a tank connection, allowing spring 38 to hold the latch against the periphery of the notch plate, preparatory to its final mating with the notch at the termination of the cycle to lock the motor M against further movement. With the latch dwelling on the periphery of the said cam plate, the valve B still maintains open channels between the ports 29 and 23 and the necessary closure of conduit 13 to port 14, allowing a continuation of the downward motion of travel. The venting line 9 at the referred position of the valve is still obstructed by the closure of ports 10 and 24.

Nearing the completion of the cycle or the termination of the downward movement, the timing of the cam lobe a' with reference to valve A is in advance of the final notching of the latch b for the purpose of maintaining motion to the ultimate destination before conduit 9 is finally vented to the tank.

In moving to the left by the action of the cam lobe, valve A gradually retards the flow from ports 34 to 35 by the metering action of a tapered valve portion 39. After complete closure of the ports 34 and 35, motion to a lesser degree is still continued by a needle valve 40, which shunts the aforementioned ports and allows a restricted volume to flow from conduit 30 to 11. After slight continued motion the latch b is allowed to drop into the notch of the cam plate to lock the motor M against further movement, causing the valve B to move further to the left finally opening the venting line 9 through the ports 10 and 24 to the tank conduit 11. In addition the conduit 22 is connected by reason of the ports 23 and 24 through the tank conduit 11, preparatory for the next cycle. Coupled with the timing relationship just described, the switches S₁ and S₃ again assume the position as indicated by the loading condition at that moment, as in Fig. 1a.

As previously mentioned the additional purpose

of the spring loaded valve 25 is to effect a back pressure in the return channel 18 on lowering. It is assumed in this circuit that the back pressure setting of the valve 25 is of sufficient value to slightly raise or sufficiently relieve the load of the conveyor to facilitate withdrawal of the latch. It will be noted that with an insufficient pressure setting of the valve 25 the fluid for momentary raising would by-pass from conduit 15 to conduit 30. By reason of the fact that the pressure setting of valve 25 must be sufficient to properly compensate for the unbalanced load, it is logical to assume that a slightly higher value would be adequate for the desired results. An elongated slot 41 in the member forming lobe a' is provided to permit adjustment between lobe a' and the notch of cam U.

In operation, from the previously mentioned four possible sets of conditions existing at the loading stations, and the corresponding setting of the safety electrical switches S₁ and S₂, it will be seen that it is impossible to actuate the hoist until the article at the delivery station has been removed. This will prevent the article at the delivery station from being carried on around the conveyor and possibly damaged, or if it should be an explosive such as a can of nitro-glycerine, it will prevent the movement to any other undesired or dangerous position. Any standard mechanism can be utilized for effecting this automatic stop, and one possible structure is shown in all the drawings as being a solenoid, operated by two two-point switches interposed by a four-way switch.

When the motor is to be moved in a hoisting direction, the directional valve D is shifted from its position as shown to a position connecting line 22 with line 17. As soon as auxiliary control valve B is shifted by pressure from valve C to the position shown in Fig. 3, pressure from line 3 will effect a hoisting movement of the motor. This will continue until latch b drops in cam U to close line 3 from line 22.

From the present disclosure it will thus be seen there has not only been produced a combination of station controls and cooperating valve controls suitable for the safe conveying of articles, but a mechanism that contains a minimum number of parts that might be apt to require attention or replacement.

What I claim is:

1. In a hydraulic actuating and control system for controlling the movements of an endless conveyor extending between spaced loading and delivery stations, a conveyor, a pressure source, a reversible conveyor motor having two ports interchangeable as pressure-exhaust ports, directional valve means for selectively directing liquid under pressure to said motor ports, a series of hydraulic conduits connecting said pressure source and said directional valve means, means for limiting the pressure in said conduits, a starting valve in said conduits adapted in one position to block flow of pressure liquid from said source and in another position to pass liquid from said source to said directional valve means, an actuating means for said starting valve, article responsive means at each of said stations to be influenced by the presence of an article at said stations and means operatively connecting said article responsive means and said directional valve means with said starting valve actuating means whereby said starting valve may be moved from its pressure blocking position only when the station toward which the conveyor will move

is empty and the station from which the conveyor will move is loaded, a locking wheel operatively connected to said motor, a latch for engaging said wheel to lock said motor, and means connected to said latch and operated by pressure directed from said starting valve for disengaging said latch from said wheel to permit operation of said motor, said starting valve being arranged to direct liquid under pressure to operate said latch means only when said starting valve is shifted from its blocking position.

2. In a hydraulic actuating and control system for controlling the movements of an endless conveyor hoist, extending between spaced loading and delivery stations, a pressure source, a reversible conveyor motor having ports interchangeable as pressure-exhaust ports, directional valve means for selectively directing liquid under pressure to said motor ports to cause hoisting or lowering action, hydraulic conduits connecting said pressure source and said directional valve means, a starting valve in said conduits adapted, in one position, to block flow of pressure liquid from said source and, in another position, to pass liquid from said source to said directional valve means, a locking wheel operatively connected to said motor, a latch for engaging said wheel to lock said motor against a downward movement, means connected to said latch and operable by pressure directed from the source through said starting valve for disengaging said latch from said wheel, and a valve in said conduits between the starting valve and the directional valve operable with said last named means and adapted to direct lifting pressure momentarily to said motor through said directional valve to permit withdrawal of said latch from said wheel and to direct pressure thereafter to said motor through said directional valve to effect lowering action, said starting valve being arranged to direct liquid under pressure to operate said latch means only when said starting valve is shifted from its blocking position.

3. In a hydraulic actuating and control system for controlling the movements of an endless hoist conveyor extending between spaced upper and lower loading and delivery stations, a pressure source, a reversible hydraulic conveyor motor having two ports interchangeable as pressure and exhaust ports, a directional valve means, an auxiliary control valve, supply and return conduits connecting said directional valve with said motor and with said auxiliary control valve, said conduits to be used interchangeably as pressure and exhaust conduits, a tank conduit leading from said directional control, a starting valve, conduits connecting said starting valve with said pressure source and with said auxiliary control valve, said starting valve being adapted in one position to block flow of pressure liquid from said source and in another position to pass liquid from said source to said auxiliary valve to actuate the same, said auxiliary valve being adapted in one position, to pass liquid under pressure to one of said conduits leading to the directional valve and in another position to pass pressure liquid to the other of said conduits leading to said directional valve, locking means operably connected with said motor to prevent lowering, and means for disengaging said locking means, said valves cooperating to effect momentary lifting action of said conveyor motor to permit disengaging of said latch, and to effect thereafter a lowering action of said motor.

4. In a hydraulic actuating and control system

for controlling the movements of an endless conveyor hoist extending between spaced upper and lower loading and delivery stations, a pressure source, a reversible conveyor motor having one port to be used as a pressure port for hoisting and as an exhaust port for lowering, and a second port to be used as a pressure port for lowering and as an exhaust port for hoisting, a locking means comprising a movable part operatively connected with said motor, and a movable latch for engaging said movable part to lock the same against movement, means for withdrawing said latch, and valve means to be automatically actuated at the start of a lowering movement for momentarily directing liquid under pressure to the hoist pressure port of said motor to permit withdrawal of said latch and thereafter directing pressure to said lower pressure port.

5. In a hydraulic actuating and control system for controlling the movements of an endless conveyor hoist extending between spaced upper and lower loading and delivery stations, a reversible motor to serve as a power unit for said hoist, a releasable holding means for said motor, means for releasing said holding means, directional and starting means responsive to load conditions, for controlling the movement of said motor, and means responsive to said directional and starting means for causing a momentary hoisting action of said motor before a lowering action to permit release of said holding means.

6. In a hydraulic actuating and control system for controlling the movements of an endless conveyor hoist extending between spaced upper and lower loading and delivery stations, a pressure source, a hydraulic motor having one port to be used as a pressure port for hoisting and an exhaust port for lowering, and a second port to be used as pressure port for lowering and an exhaust port for hoisting, an auxiliary control valve, hydraulic connections between said valve and said pressure source, two conduit lines connecting said auxiliary valve with said motor ports, a directional valve in said two lines adapted in one position to open each of said motor ports, respectively, to a connecting line leading to the auxiliary control valve, and in another position to open one of said lines to the pressure lowering motor port, a locking means for said conveyor comprising a movable part and a latch for engaging said movable part, said auxiliary control valve being adapted in one position to direct pressure through one of said lines to the pressure hoisting port of said motor to effect momentary lifting movement to permit release of said latch means, and in another position, to effect lowering of said hoist, and means to effect shifting of said auxiliary valve.

7. In a hydraulic actuating and control system for controlling the movements of an endless conveyor hoist extending between spaced upper and lower loading and delivery stations, a pressure source, a hydraulic motor having one port to be used as a pressure port for hoisting and an exhaust port for lowering, and a second port to be used as a pressure port for lowering and an exhaust port for hoisting, an auxiliary control valve, hydraulic connections between said valve and said pressure source, two conduit lines connecting said auxiliary valve with said motor ports, a directional valve in said two lines adapted in one position to open each of said motor ports, respectively, to a connecting line leading to the auxiliary control valve, and in another position to

open one of said lines to the pressure lowering motor port, a locking means for said conveyor comprising a movable part and a latch for engaging said movable part, said auxiliary control valve being adapted in one position to direct pressure through one of said lines to the pressure hoisting port of said motor to effect momentary lifting movement to permit release of said latch means, and in another position, to effect lowering of said hoist, and a starting control valve in said system adapted in one position to block flow of pressure liquid from said source, and in a second position to pass pressure liquid from said source to said auxiliary valve to shift the same from the momentary lifting position to a pressure lowering position.

8. In a hydraulic actuating and control system for controlling the movements of an endless conveyor extending between spaced loading stations, 20 a liquid supply tank, a pressure source, a conveyor motor, lines between said motor and said pressure source, a starting control valve in said lines, an auxiliary line between said valve and said tank, and a relief valve connected to said lines between said starting control valve and said pressure source, said relief valve comprising a housing provided with a cylinder connected at one end by said lines to the pressure source and to the tank and connected at a second end by 25 said lines to said starting control valve, a piston shiftable in said cylinder having a restricted passageway therethrough and means thereon for normally blocking the tank connection of the cylinder, said starting control valve being adapted 30 in one position to permit flow of pressure liquid from the source to said motor and to close said second end of the relief valve cylinder from the tank, and in a second position to block flow of 35 pressure liquid from the pressure source and to open the second end of the relief valve cylinder to the tank, whereby pressure liquid from the pressure source may actuate said relief valve piston to open the tank connection of the cylinder and bypass the pressure flow, means associated 40 with said motor for controlling the direction of movement thereof, and auxiliary means associated with and responsive to movement of said starting valve for directing liquid under pressure 45 momentarily to drive said motor in one direction immediately prior to prolonged movement in the other direction.

9. In a hydraulic actuating and control system for controlling the movements of an endless conveyor hoist extending between spaced loading stations, 55 a liquid supply tank, a pressure source, a conveyor motor, directional means associated with said motor movable to a lifting or lowering position for controlling the direction of movement thereof, an auxiliary control valve, a starting valve, lines connecting said valves, pressure source and directional means, said valves being arranged to cooperate in one position to block pressure flow from said source to said directional means, and each being movable to a second position to permit flow through said lines to cause a 60 momentary lifting movement and a prolonged lowering movement of said motor when said directional means is set for lowering movement and a prolonged lifting movement when said directional means is set for lifting movement.

10. In a hydraulic actuating and control system for controlling the movements of an endless conveyor hoist extending between spaced loading stations, a liquid supply tank, a pressure source, 65 a conveyor motor, directional means associated

with said motor movable to a lifting or lowering position for controlling the direction of movement thereof, an auxiliary control valve, a starting valve, lines connecting said valves, pressure source and directional means, said valves being arranged to cooperate in one position to block pressure flow from said source to said directional means, and each being movable to a second position to permit flow through said lines to cause a momentary lifting movement and a prolonged lowering movement of said motor when said directional means is set for lowering movement and a prolonged lifting movement when said directional means is set for lifting movement, a relief valve in said lines normally maintained in closed position by pressure, said starting and auxiliary control valves being adapted to control the pressure closing said relief valve whereby said relief valve will remain open until said starting valve is shifted.

11. In a hydraulic actuating and control system for controlling the movements of an endless conveyor hoist extending between spaced loading stations, a liquid supply tank, a reversible conveyor motor, a pump, a hydraulic control circuit for directing pressure from said pump to said motor, and means for controlling the speed of said motor at predetermined times in the cycle of movement of said conveyor comprising a deceleration valve adapted in one position to pass exhaust liquid from said motor to the tank, and means responsive to the movement of said motor for shifting said valve to cut off gradually the exhaust flow to the tank, and a second valve means located in parallel with said deceleration valve and adapted to further restrict the flow of exhaust liquid upon the shifting of said deceleration valve.

12. In a hydraulic actuating and control system for controlling the movements of an endless conveyor extending between spaced loading stations, a pressure source, a conveyor motor, directional means associated with said motor to control the direction of movement thereof, a starting valve, an auxiliary control valve, lines connecting said valves, pressure source, and directional means, said starting valve being adapted to be momentarily shifted in response to certain load conditions at said stations to direct pressure from said source to said auxiliary control valve to shift the same, means for maintaining said control valve in shifted position for a predetermined movement of said motor, said control valve being adapted, when in one position, to direct pressure from said starting valve to said directional means to effect momentary movement of said motor in one direction, and, when shifted, to direct pressure from said source to said directional means to effect prolonged movement of said motor in the other direction.

13. In a hydraulic actuating and control system for controlling the movements of an endless conveyor extending between spaced loading stations, a pressure source, a conveyor motor, directional means associated with said motor, to control the direction of movement thereof, a starting valve, an auxiliary control valve, lines connecting said valves, pressure source, and directional means, a pressure controlled relief valve in said lines associated with said starting valve, said starting valve being adapted to be momentarily shifted in response to certain load conditions at said stations to direct pressure from said source to said auxiliary control valve to shift the

same and to effect closing of said relief valve, means for maintaining said control valve in shifted position for a predetermined movement of said motor, said control valve being adapted, when in one position, to direct pressure from said starting valve to said directional means to effect momentary movement of said motor in one direction, and, when shifted, to direct pressure from said source to said directional means to effect prolonged movement of said motor in the other direction.

14. In a hydraulic actuating and control system for controlling the movements of an endless conveyor extending between spaced loading stations, a pressure source, a conveyor motor, directional means associated with said motor to control the direction of movement thereof, a starting valve, an auxiliary control valve, lines connecting said valves, pressure source, and directional means, said starting valve being adapted to be momentarily shifted in response to certain load conditions at said stations to direct pressure from said source to said auxiliary control valve to shift the same, means for maintaining said control valve in shifted position for a predetermined movement of said motor, said control valve being adapted, when in one position, to direct pressure from said starting valve to said directional means to effect momentary movement of said motor in one direction, and, when shifted, to direct pressure from said source to said directional means to effect prolonged movement of said motor in the other direction, and valve means for controlling the pressure utilized for said momentary lifting.

15. In a hydraulic actuating and control system for controlling the movements of an endless conveyor extending between spaced loading stations, a supply tank, a pump, a supply line leading from said pump, a relief valve in said supply line comprising a piston valve for closing said supply line from the tank and a pressure chamber behind said valve for holding it in closed position, a starting valve and an auxiliary valve, each connected to said supply line, a conveyor motor to be operated by pressure from said pump, receiving lines connecting said auxiliary control valve and said motor, a directional valve in said receiving lines for directing pressure to and from said motor, said starting valve being adapted in one position to connect said relief valve pressure chamber through said auxiliary control valve to the tank and to block flow from the supply line leading thereto and being shiftable to a second position to close said relief valve pressure chamber, and to open said supply line to a receiving line through said auxiliary control valve and to direct pressure to said auxiliary control valve to shift the same, said auxiliary control valve being adapted in one position to block the supply line leading thereto and to pass pressure flow from the starting valve to a receiving line to effect momentary movement of said motor in one direction, and being shiftable by pressure from said starting valve to a second position in which said supply line is open directly to another of said receiving lines to effect a movement of said motor in the other direction, and in which said relief valve pressure chamber is closed, and means responsive to movement of said motor for maintaining said auxiliary control valve in said second position for a predetermined movement of said motor.

HARRY F. VICKERS.
